UNITED STATES PATENT OFFICE.

ERNEST C. SCHRADER, OF MORGANTOWN, WEST VIRGINIA, ASSIGNOR TO ECONOMY GLASS COMPANY, OF MORGANTOWN, WEST VIRGINIA, A CORPORATION OF WEST VIRGINIA.

DESIGN FOR A TUMBLER OR SIMILAR ARTICLE OF GLASSWARE.

Application filed January 31, 1927. Serial No. 20,552. Term of patent 3½ years.

To all whom it may concern:

Be it known that I, ERNEST C. SCHRADER, a citizen of the United States, residing at Morgantown, in the county of Monongalia and State of West Virginia, have invented a new, original, and ornamental Design for a Tumbler or Similar Article of Glassware, of which the following is a specification, reference being had to the accompanying drawing, forming a part thereof.

The figure illustrates a side elevation of a tumbler showing my new design.

I claim:

The ornamental design for a tumbler or similar article of glassware as shown.

ERNEST C. SCHRADER.
